UNITED STATES PATENT OFFICE.

SERVETUS T. ACHOR, OF BROOKLYN, NEW YORK.

ADJUSTABLE PARTITION FOR BOXES.

SPECIFICATION forming part of Letters Patent No. 374,920, dated December 20, 1887.

Application filed July 29, 1887. Serial No. 245,646. (Model.)

To all whom it may concern:

Be it known that I, SERVETUS T. ACHOR, a citizen of the United States and of the State of New York, residing at the city of Brooklyn, 5 Kings county, New York, have invented certain new and useful Improvements in Adjustable Partitions for Boxes, of which the following is a specification.

My invention relates to a movable partition for dividing the interior of boxes and similar packages into subdivisions of various capacities, so that the same box may be made to contain articles of various kinds without their becoming mixed together and confused, or 10 articles of the same kind may be separated into smaller masses, so as to avoid bruising or crushing; and my invention is particularly adapted for use in boxes containing confectionery, which is liable to be crushed by its own weight when in large masses, or to adhere 15 together in warm weather. It is also adapted for use in packing fruits, and for many other articles.

In the drawings, Figure 1 is a side view of 25 a box fitted with my improved partitions, with the side of the box broken away. Fig. 2 is a sectional view of the same on line *x y*. Fig. 3 shows one of the metal supports. Figs. 4, 5, 6, 7, and 8 are modifications of the form of 30 the support; and Fig. 9 is a plan view, looking down from above, of the sheet *K*, partitions *C*, and supports *D*.

Similar letters of reference designate similar parts in all the drawings.

35 A is an ordinary box, provided with a lid, *B*. *C C C* are strips of pasteboard, veneer, or similar material, and *D D D* are strips of tin or sheet metal bent into the form shown and adapted to straddle and support the strips *C* 40 *C C*. The lower flanges, *G G*, of the supports *D D D* are provided with downwardly-extending points or projections, as *E E E E*, which may be formed in various ways, as by bending down the corners, as shown in Figs. 45 3 and 5, or by projecting points, as shown in Figs. 6, 7, and 8, or by punching holes through the flanges, thus leaving the superfluous metal in projecting points, as shown in Fig. 4. *L L* indicate the contents of the box.

50 In Figs. 5 and 6 the support *D* is provided with a slot, *H H*, to allow of a strip, *I*, being

inserted at right angles to the strip *C*, so as to further subdivide the box, if desired.

In use one or more of the supports *D* are placed across each of the strips *C*, which strips 55 are then placed at such distances along the box as to divide it into spaces of the desired size, the supports *D* keeping the partitions *C* in an erect position. If the box is to be divided by more than one tier of partitions, a sheet, *K*, 60 of card-board or similar material is then placed on top of the partitions and a second tier is arranged thereupon, and this is proceeded with until the requisite number of tiers has been arranged. Any vacaney at the top of 65 the box should be filled up, so that the supports will be held between the lid and bottom of the box. The weight or pressure will cause the projections on the flanges or bases *G* to catch on the flat material beneath them, so as 70 to prevent the supports *D D* and partitions *C* from slipping or changing their positions.

The neatest and most satisfactory means of construction is to make the parts of such proportions that a certain number—one or more— 75 of tiers will evenly fill the box, thus holding the supports directly between the lid and bottom; but, as I have said, any space at the top can be filled up and the result will be the same.

The supports *D D* have sufficient strength to 80 bear all ordinary weight and pressure which is put upon them, and the more downward pressure they have upon them the more firmly they are held in their places. They thus sustain the pressure which would at once bend 85 over or break the partitions *C C* if unsupported, and form a firm and convenient package.

My invention is cheap and easily manufactured and applied, it wears well, is not liable to be easily broken, and is in many respects a most valuable improvement. It is susceptible of various modifications, which do not, however, affect the merits of the invention. One of these modifications is shown in Figs. 7 90 and 8, where the points *E E* are sharp and bent at such an angle as to penetrate the material beneath them, and, catching therein, give a still firmer hold to the support.

Having thus described my invention, what I 100 claim, and desire to secure by Letters Patent of the United States, is—

1. The combination, with a box provided with a lid, of a vertical partition supported by a metallic strip, said strip being provided with a horizontal base to rest upon and projecting 5 points to engage with the bottom of the box, substantially as and for the purposes set forth.

2. The combination, with a box, of a partition, C, and a metallic support, D, provided with flanges G G and projections E E, substantially as and for the purposes set forth.

3. The combination, with a box, A, and lid B, of two or more tiers of strips, C C, each having a support, D, provided with flanges G G and projections E E, and a sheet, K, interposed between the adjacent tiers, substantially 15 as and for the purposes set forth.

SERVETUS T. ACHOR.
